UNITED STATES PATENT OFFICE

2,002,903

APPARATUS FOR MAKING RADIATORS

James F. McIntire, Detroit, Mich., assignor to
United States Radiator Corporation, Detroit,
Mich., a corporation of New York

Original application August 15, 1932, Serial No.
628,950. Divided and this application March
19, 1934, Serial No. 716,420

18 Claims. (Cl. 22—131)

This invention relates generally to the manufacture of radiators and constitutes a division of my application filed August 15, 1932, bearing Serial No. 628,950.

5 One of the essential objects of the invention is to provide an efficient means for manufacturing radiators which is less involved than the usual molding process and apparatus wherein flasks and green sand are employed.

10 Another object is to provide a means for manufacturing radiators which avoids the usual molding operations and eliminates entirely the use of metal flasks, the necessity of making green sand molds, the contact of molten metal with improperly conditioned green sand, and the consequent sand tempering and loss of green sand.

15 Another object is to provide a means for manufacturing radiators which may be utilized entirely in the core room.

20 Other objects, advantages and novel details of construction of this invention will be made more apparent as this description proceeds, especially when considered in connection with the accompanying drawings, wherein:

25 Figure 1 is a perspective view of molding apparatus embodying my invention;

Figure 2 is a vertical transverse sectional view through the apparatus illustrated in Figure 1, with parts broken away at the top;

30 Figure 3 is a horizontal sectional view through a portion of the structure illustrated in Figure 2 and taken approximately on the line 3—3 thereof;

35 Figure 4 is a vertical longitudinal sectional view through a portion of the structure illustrated in Figure 3 and taken approximately on the line 4—4 thereof;

Figure 5 is a vertical transverse sectional view taken on the line 5—5 of Figure 3;

40 Figure 6 is a perspective view of one of the header body cores illustrated in Figure 3;

Figure 7 is a fragmentary perspective view of one of the fluidway cores illustrated in Figure 3;

45 Figure 8 is a fragmentary bottom plan view of the cover core illustrated in Figure 5;

Figures 9 and 9A are perspective views of opposite sides of one of the header cores;

50 Figures 10 and 10A are perspective views of opposite sides of one of the fin cores;

Figure 11 is a fragmentary top plan view of a radiator of the double fluidway type adapted to be formed in the apparatus illustrated in

Figure 12 is a sectional view taken on the line 12—12 of Figure 11;

Figure 13 is a sectional view taken on the line 13—13 of Figure 11.

Referring now to the drawings, A is a radiator of the double fluidway type, and B designates generally the apparatus in which such a radiator may be formed. As shown, the radiator A has end walls 1, side walls 2 terminally secured to the end walls at the upright edges thereof, headers 3 upon the inner sides of the end walls, fluidways 4 and 5 respectively extending between the headers 3 and disposed in parallel relation to the side walls 2, a partition 6 extending between the headers 3 substantially midway between and in parallel relation to the fluidways 4 and 5, fins 7 and 8 respectively projecting laterally from the outer walls 9 and 10 respectively of the fluidways to the side walls 2, and fins 11 and 12 respectively projecting laterally from the inner walls 13 and 14 respectively of the fluidways to the partition 6. Both the side walls 2 and partition 6 have openings 15 and 16 respectively therein at spaced points longitudinally thereof. As shown, the openings 15 in the side walls 2 are arranged in vertically spaced rows, while the openings 16 in the partition 6 are in a single row located substantially midway of the upper and lower edges of said partition.

Referring now to the apparatus in which the radiator A of the double fluidway type is formed, 20 are the sprue cores, 21 are the end cores, 22 are the header cores, 23 are the fin cores, 24 and 25 are the fluidway cores, 26 are the header body cores and 27 is the cover core. As shown, there are two sprue cores 20 and each preferably comprises a relatively thick upright body or slab having flat ends 20^a and 20^b respectively. For receiving the molten metal, I have provided in the upper end 20^c of each body an upwardly flaring sprue 20^d that opens through the inner side 20^e, and have provided an inverted substantially T-shaped gate 20^f that extends downwardly from the lower end of the sprue 20^d and also opens through the inner side 20^e.

The end cores 21 are alike, and each preferably comprises a relatively thick upright body or slab having flat outer and stepped inner walls 21^a and 21^b respectively and flat upper and lower ends 21^c and 21^d respectively. Preferably the end cores 21 are higher than the sprue cores 20 and when assembled project above the upper ends 20^b of said sprue cores. The flat outer sides 21^a of the end cores are engageable with the flat inner sides 20^e of the sprue cores

and when assembled form the inner sides of the sprues 20^d and gates 20^e. The steps 21^e are flat and constitute the upper edges of plate-like portions 21^f of the slabs 21. Preferably each of these portions 21^f has a flat face 21^g in which substantially square recesses 21^h, three laterally spaced openings 21ⁱ and runners 21^k are provided for receiving the molten metal. As shown, the recesses 21^h correspond in shape to the end walls 1 of the radiator, the openings 21ⁱ extend through the bodies 21 so as to receive the molten metal from the gates 20^e; and the runners 21^k incline upwardly from the upper walls of said openings to the recesses 21^h. Thus, the molten metal from the gates 20^e will flow upwardly from the openings 21ⁱ into the recesses 21^h to form the end walls 1 of the radiator.

The header cores 22 are arranged in two series, one upon the inner side of each end core 21. As shown, each of the header cores comprises a plate that substantially corresponds in area to the plate-like portions 21^f of the end cores and having openings 22^a registering with the openings 21ⁱ. Preferably each header core 22 has a relatively wide substantially square-shaped opening 22^b extending upwardly through its upper edge and is provided upon opposite sides of said opening in one face thereof with recesses 22^c and 22^d respectively corresponding in area to the fins 7 and 8. The lower ends 22^e and 22^f respectively of these recesses and the lower edge 22^g of the opening 22^a are in line, and runners 22^h, 22ⁱ, 22^j, 22^k, 22^l and 22^m respectively extend upwardly from the openings 22^a to said aligned edges and ends 22^e, 22^f and 22^g respectively. Webs 22ⁿ and 22^p respectively corresponding in area to the openings 15 and slots 22^q corresponding in area to the cross section of the side walls 2 are provided along the upright edges 22^r and 22^s respectively of the recesses 22^c and 22^d.

The fin cores 23 correspond in area to the header cores 22 and have openings 23^a registering with the openings 22^a in the header cores. As shown, each fin core 23 has a pair of laterally spaced elongated openings 23^b and 23^c extending upwardly through its upper edge and is provided in one face thereof upon opposite sides of said openings with recesses 23^d, 23^e, 23^f and 23^g respectively corresponding in area to the fins 7, 12, 11 and 8. Preferably the lower ends 23^h, 23ⁱ, 23^j and 23^k respectively, of these recesses are in line just below the openings 23^b and 23^c. Slots 23^l and 23^m respectively extend downwardly from the lower ends of the openings 23^b and 23^c to said aligned ends 23^h, 23ⁱ, 23^j and 23^k, while runners 23ⁿ, 23^p, 23^q, 23^r and 23^s respectively extend upwardly from the openings 23^a to the aligned lower ends of said recesses. Webs 23^t corresponding in area to the openings 15, and slots 23^u corresponding in area to the cross section of the side walls 2 are provided along the upright edges 23^v and 23^w respectively of the recesses 23^d and 23^g, while slots 23^x corresponding in area to the cross section of the partition 6, and an intermediate web 23^y corresponding in area to one of the openings 16 are provided in a vertical line 70 between the recesses 23^e and 23^f. In this connection it will be noted that the upper edge portion 23^z of the core part intermediate the openings 23^b and 23^c is reduced in thickness and is provided with vents 23^{xx} for core gases so as to prevent undue pressure and distortion while

the metal is flowing within the recesses 23^e and 23^f.

The fluidway cores 24 and 25 extend between the end cores 21 and each preferably has a pair of substantially rectangular header portions 24^a and an intermediate web portion 24^b. As shown, the header portions 24^a are received in the openings 22^b in the header cores and are provided at approximately the center of their opposed sides with substantially square-shaped prints 24^c. The web portions 24^b are received in the openings 23^b and 23^c and merge into the header portions 24^a at the outer sides thereof. The lower edges 24^d of the webs are rounded or curved transversely as shown and are held in place in the openings 23^b and 23^c by suitable chaplets 24^e, while the upper edges 24^f of the webs are flat and are held in place in the openings by suitable chaplets 24^g. To permit the escape of core gases, the fluidway cores 24 and 25 have longitudinally and transversely extending passages 24^h and 24ⁱ respectively therein, the transverse passages 24ⁱ being at opposite ends of the longitudinal passages and extending through the prints 24^c.

The header body cores 26 are preferably blocks of substantially rectangular configuration that are located between the header portions 24^a of the fluidway cores and have recesses 26^a in opposite sides thereof receiving the prints 24^c. As shown, each header core 26 has a transverse passage 26^b extending between the recesses 26^a and has a vertical passage 26^c for the escape of core gases.

The cover core 27 is in the form of a slab and extends between the end cores 21. Preferably this core 27 has a flat body 27^a that rests upon the steps 21^e of the end cores and upon the upper edges of the header and fin cores 22 and 23. Opposite ends 27^c of said body are substantially rectangular in shape and cover the openings 22^b in the header cores, while the intermediate portion of said body comprises a pair of parallel strips 27^d and 27^e that cover the openings 23^b and 23^c respectively in the fin cores. Projecting downwardly from the end portions 27^e of said body are substantially rectangular-shaped portions 27^f that fit within the openings 22^b in the header cores, while projecting downwardly from the strip portions 27^d and 27^e are ribs 27^g and 27^h that fit within the openings 23^b and 23^c respectively in the fin cores. To permit the escape of core gases, suitable openings 27ⁱ are provided in the cover core at opposite ends thereof for registration with the vertical passages 26^c in the header body cores 26.

In the present instance, the sprue cores 20 and cores 21, header cores 22, fin cores 23, fluidway cores 24 and 25, header body cores 26 and cover core 27 of the apparatus are dry sand cores. In use, the cores 20, 21, 22 and 23 are assembled and clamped in a suitable rack C (see Figure 1). The fluidway cores 24 and 25 with the chaplets 24^e and 24^g thereon are assembled with the header body cores 26 and such sub-assembly is then placed in the openings 22^b and 23^b and 23^c respectively in the header and fin cores, and finally the cover core 27 is placed upon the steps 21^b of the end cores and upon the upper edges of the header and fin cores. In this connection it will be noted that the lower end 30 and opposite sides 31 and 32 respectively of certain of the openings 23^b and 23^c are engaged by the chaplets 24^e, while the opposite sides 31 and 32 and the lower faces of the ribs 75

27^g and 27^h are engaged by the chaplets 24^g. Thus, the fluidway cores 24 and 25 are effectively held in position for the pouring of the molten metal.

5 After the parts have been assembled as described, the molten metal may be poured into either or both of the sprues 20^d and will flow through the gates 20^f, openings 21ⁱ, 22^a, 23^a, 23^b and 23^c upwardly through the runners 21^k, 22^h, 10 22ⁱ, 22^j, 22^k, 22^l and 22^m, 23ⁿ, 23^p, 23^q, 23^r and 23^s to the recesses 21^h, 22^c, 22^d, 23^d, 23^e, 23^f, 23^g, 15 slots 22^q, 23^u and 23^v to form the radiator. Thus, it will be apparent that the end walls 1 will be formed in the recesses 21^h in the end cores 21, 20 the side walls 2 will be formed in the slots 22^q and 23^u in the header and fin cores 22 and 23 respectively, the headers 3 and fluidways 4 and 5 will be formed in the openings 22^b, 23^b and 23^c respectively in the header and fin cores, and the 25 fins 7, 8, 11 and 12 respectively will be formed in the recesses 22^c, 23^d, 22^d, 23^e, 23^f and 23^g respectively in the header and fin cores. The cover core 27 cooperates with the end, header and fin cores 21, 22 and 23 respectively to form the upper end of the headers 3 and the top walls of the fluidways 4 and 5.

What I claim as my invention is:

1. A mold for forming a radiator having end and side walls, headers upon the end walls, substantially parallel fluidways extending between the headers, and fins projecting laterally from opposite sides of said fluidways, comprising substantially parallel longitudinally extending dry sand cores having relatively thin elongated bodies for forming the fluidways and having enlargements at opposite ends thereof, cores of block-like configuration between and cooperating with said enlargements for forming the headers, and a casing for said cores comprising slabs at opposite ends of said cores in spaced relation to the enlargements, vertically disposed fin cores arranged one against the other in a row between said enlargements and having substantially horizontal and vertical portions respectively spaced beneath, between and upon the outer sides of said longitudinally extending cores, vertically disposed header cores arranged one against the other between the slabs and fin cores and having substantially horizontal and vertical portions respectively spaced beneath and upon the outer sides of said longitudinally extending cores, the said slabs being provided in their inner faces with recesses into which metal may flow to form the end walls of the radiator, one of said slabs being provided with an opening for receiving molten metal and having a runner for conducting such metal to said recess, the header cores being provided in horizontal alignment with the recesses aforesaid with recesses into which metal may flow to form the second mentioned fins, the fin cores being provided in horizontal alignment with the recesses aforesaid with recesses into which metal may flow to form the first mentioned fins, the bases of the recesses in the fin and header cores being provided with aligned slots into which metal may flow to form the side walls of the radiator, the fin and header cores being provided with openings that are in communication with and adapted to receive metal from the opening in the slab aforesaid and having runners for conducting such metal from said openings to the recesses therein.

3. A mold for forming a radiator having end and side walls, headers upon the end walls, substantially parallel fluidways extending between said headers, a partition extending between said headers and disposed substantially midway between said fluidways, fins projecting laterally from the inner sides of said fluidways to said partition, and fins projecting from the outer sides of said fluidways to said side walls, comprising substantially parallel longitudinally extending dry sand cores having relatively thin elongated bodies for forming the fluidways and having enlargements at opposite ends thereof, cores of block-like configuration between and cooperating with said enlargements for forming the headers, and a casing for said cores comprising slabs at opposite ends of said longitudinally extending cores in spaced relation to the enlargements, vertically disposed fin cores arranged one against the other in a row between said enlargements and having substantially horizontal and vertical portions respectively spaced beneath, between and upon the outer sides of said elongated bodies, vertically disposed header cores arranged one against the other in rows between the slabs and the adjacent fin cores aforesaid and having substantially horizontal and vertical portions respectively spaced beneath and upon the outer sides of said enlargements,

2. A mold for forming a radiator having end and side walls, headers upon the end walls, substantially parallel fluidways extending between

and a cover core extending over the vertical portions of said fin and header cores between said slabs, the said slabs being provided in their inner faces with recesses into which metal may flow to form the end walls of the radiator, one of said slabs being provided with an opening for receiving molten metal and having a runner for conducting said metal to the recess therein, the fin cores being provided in horizontal alignment with the recesses aforesaid with recesses into which metal may flow to form the fins aforesaid, the vertical portions of said fin cores between the elongated bodies aforesaid having aligned slots into which metal may flow to form the partition of the radiator, the said fin cores and header cores having horizontally aligned slots into which metal may flow to form the side walls of the radiator, the fin and header cores having openings in communication with and adapted to receive metal from the opening in the slab aforesaid and having runners for conducting such metal from said openings to the spaces between the vertical portions thereof.

4. A mold for forming a radiator having end and side walls, headers upon the end walls provided with fluid openings, substantially parallel fluidways extending between the headers, and fins projecting laterally from opposite sides of said fluidways, comprising substantially parallel longitudinally extending dry sand cores having relatively thin elongated bodies for forming the fluidways and having enlargements at opposite ends thereof, cores of block-like configuration between and cooperating with said enlargements for forming the headers, said block-like cores being provided with prints for forming the fluid openings, and a casing for said cores comprising slabs at opposite ends of the longitudinally extending cores in spaced relation to the enlargements, vertically disposed fin cores arranged one against the other in a row between said enlargements and having substantially horizontal and vertical portions respectively spaced beneath, between and upon the outer sides of said elongated bodies, vertically disposed header cores arranged one against the other in rows between the slabs and the adjacent fin cores and having substantially horizontal and vertical portions respectively spaced beneath and upon the outer sides of said enlargements, and a cover core extending over the vertical portions of the fin and header cores between said slabs, the said slabs being provided in their inner faces with recesses into which metal may flow to form the end walls of the radiator, one of said slabs being provided with an opening for receiving molten metal and having a runner for conducting such metal to the recess therein, the fin cores being provided in horizontal alignment with the recesses aforesaid with recesses into which metal may flow to form the fins of the radiator, the fin cores and the header cores being provided with aligned slots into which metal may flow to form the side walls of the radiator, the fin and header cores having openings in communication with and adapted to receive metal from the opening in the slab aforesaid and having runners for conducting such metal from the openings to the spaces between the vertical portions thereof.

5. A mold for forming a radiator having end and side walls, headers upon the end walls, and substantially parallel fluidways extending between the headers, comprising substantially parallel longitudinally extending dry sand cores

for forming the fluidways, cores of block-like configuration between and cooperating with said longitudinally extending cores for forming the headers, and a casing for said cores comprising slabs at opposite ends of said longitudinally extending cores, vertically disposed plate-like cores arranged one against the other in a row between said slabs and having substantially horizontal and vertical portions respectively spaced beneath, between and upon the outer sides of said longitudinally extending cores, vertically disposed plate-like cores arranged one against the other in rows between the slabs and the adjacent plate-like cores just mentioned and having substantially horizontal and vertical portions respectively spaced beneath and upon the outer sides of said longitudinally extending cores, and a cover core extending over the vertical portions of said plate-like cores between said slabs, the said slabs being provided in their inner faces with recesses into which metal may flow to form the end walls of the radiator, one of said slabs being provided with an opening for receiving molten metal and having a runner for conducting said metal to the recess therein, the plate-like cores having horizontally aligned slots into which metal may flow to form the side walls of the radiator, the plate-like cores having openings in communication with and adapted to receive molten metal from the opening in the slab aforesaid and having runners for conducting such metal from said openings to the spaces between the upright portions thereof.

6. A mold for forming a radiator having end and side walls, headers upon the end walls, substantially parallel fluidways extending between the headers, and a partition disposed substantially midway between the fluidways and terminally connected to the headers, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed plate-like cores arranged one against the other in a row between said slabs and having substantially horizontal and vertical portions respectively beneath, between and upon the outer sides of said longitudinally extending cores, vertically disposed plate-like cores arranged one against the other in rows between the slabs and the adjacent plate-like cores just mentioned and having substantially horizontal and vertical portions respectively spaced beneath and upon the outer sides of said longitudinally extending cores, and a cover core extending over the vertical portions of said plate-like cores between said slabs, the said slabs being provided in their inner faces with recesses into which metal may flow to form the end walls of the radiator, one of said slabs being provided with an opening for receiving molten metal and having a runner for conducting said metal to the recess therein, the plate-like cores being provided substantially in alignment with the outer upright edges of the recesses in the slabs with aligned slots into which metal may flow to form the side walls of the radiator, the vertical portions of the first mentioned plate-like cores between the longitudinally extending cores aforesaid having aligned slots into which metal may flow to form the 70 side walls of the radiator, the vertical portions of the second mentioned plate-like cores between the longitudinally extending cores aforesaid having aligned slots into which metal may flow to form the 75 side walls of the radiator.

partition of the radiator, the plate-like cores also having openings in communication with and adapted to receive molten metal from the opening in the slab aforesaid and having runners for conducting such metal from said openings to the spaces between the upright portions thereof.

7. A mold for forming a radiator having end and side walls, headers upon the end walls, substantially parallel fluidways extending between the headers, a partition disposed between said fluidways and terminally connected to said headers, and fins projecting laterally from opposite sides of said fluidways, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed fin cores arranged one against the other in a row between said slabs and having substantially horizontal and vertical portions respectively spaced beneath, between and upon the outer sides of said longitudinally extending cores, vertically disposed header cores arranged one against the other between the slabs and fin cores and having substantially horizontal and vertical portions respectively spaced beneath and upon the outer sides of said longitudinally extending cores, and a cover core extending over the vertical portions of said header and fin cores between said slabs, the said slabs being provided in their inner faces with recesses into which metal may flow to form the end walls of the radiator, one of said slabs being provided with an opening for receiving molten metal and having a runner for conducting said metal to the recesses therein, the fin cores being provided upon the outer sides of said longitudinally extending cores in horizontal alignment with the recesses aforesaid with recesses into which metal may flow to form the fins of the radiator, the fin cores and the header cores having horizontally aligned slots into which metal may flow to form the side walls of the radiator, the vertical portions of said fin cores between the longitudinally extending cores aforesaid having aligned slots into which metal may flow to form the partition of the radiator, the header and fin cores having openings in communication with and adapted to receive molten metal from the opening in the slab aforesaid and having runners for conducting such metal from said openings to the spaces between the upright portions thereof.
9. A mold for forming a radiator having end and side walls, headers upon the end walls substantially parallel fluidways extending between the headers, a partition between the fluidways terminally connected to the headers, and fins projecting laterally from the inner sides of the fluidways to said partition, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed fin cores arranged one against the other in a row between said slabs and having substantially horizontal and vertical portions respectively spaced beneath, between and upon the outer sides of said longitudinally extending cores, vertically disposed header cores arranged one against the other between the slabs and fin cores and having substantially horizontal and vertical portions respectively spaced beneath and upon the outer sides of said longitudinally extending cores, and a cover core extending over the vertical portions of said header and fin cores between said slabs, the said slabs being provided in their inner faces with recesses into which metal may flow to form the end walls of the radiator, one of said slabs being provided with an opening for receiving molten metal and having a runner for conducting said metal to the recesses therein, the fin cores being provided upon the outer sides of the longitudinally extending cores in horizontal alignment with the recesses aforesaid with recesses into which metal may flow to form the fins of the radiator, the vertical portions of the fin cores between the longitudinally extending cores aforesaid having aligned slots into which metal may flow to form the partition of the radiator, the header and fin cores having openings in communication with and adapted to receive molten metal from the opening in the slab aforesaid and having runners for conducting such metal from said openings to the spaces between the upright portions thereof.
8. A mold for forming a radiator having end and side walls, headers upon the end walls, substantially parallel fluidways extending between the headers, a partition disposed between the fluidways and terminally connected to the headers, and fins projecting laterally from the outer sides of said fluidways to said side walls, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed fin cores arranged one against the other in a row between said slabs and having substantially horizontal and vertical portions respectively spaced beneath, between and upon the outer sides of said longitudinally extending cores, and a cover core extending over the vertical portions of said header and fin cores between said slabs, the said slabs being provided in their inner faces with recesses into which metal may flow to form the end walls of the radiator, one of said slabs being provided with an opening for receiving molten metal and having a runner for conducting said metal to the recesses therein, the fin cores being provided upon the outer sides of the longitudinally extending cores in horizontal alignment with the recesses aforesaid with recesses into which metal may flow to form the fins of the radiator, the vertical portions of the fin cores between the longitudinally extending cores aforesaid having aligned slots into which metal may flow to form the partition of the radiator, said fin and header cores having horizontally aligned slots into which metal may flow to form the side walls of the radiator, the header and fin cores having open-

ings in communication with and adapted to receive molten metal from the opening in the slab aforesaid and having runners for conducting such metal from said openings to the spaces between the upright portions thereof.

10. A mold for forming a radiator having end and side walls, headers upon the end walls, substantially parallel fluidways extending between the headers, a partition disposed between the fluidways and terminally connected to the headers, fins projecting laterally from opposite sides of the fluidways to said partition and side walls respectively, and fins projecting laterally from the outer sides of said headers to said side walls, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed fin cores arranged one against the other in a row between said slabs and having substantially horizontal and vertical portions respectively spaced beneath, between and upon the outer sides of said longitudinally extending cores, vertically disposed header cores arranged one against the other between the slabs and fin cores and having substantially horizontal and vertical portions respectively spaced beneath and upon the outer sides of said longitudinally extending cores, and a cover core extending over the vertical portions of said header and fin cores between said slabs, the said slabs being provided in their inner faces with recesses into which metal may flow to form the end walls of the radiator, one of said slabs being provided with an opening for receiving molten metal and having a runner for conducting said metal to the recess therein, the fin cores being provided upon the inner sides of the longitudinally extending cores in horizontal alignment with the recesses aforesaid with recesses into which metal may flow to form the first mentioned fins of the radiator, the header cores being provided upon the outer sides of the longitudinally extending cores in horizontal alignment with the recesses in the slabs with recesses into which metal may flow to form the last mentioned fins of the radiator, the bases of the recesses in the fin and header cores being provided with horizontally aligned slots into which metal may flow to form the side walls of the radiator, the vertical portions of the fin cores between the longitudinally extending cores aforesaid having aligned slots into which metal may flow to form the partition of the radiator, the header and fin cores having communicating openings in communication with and adapted to receive molten metal from the opening in the slab aforesaid and having runners for conducting such metal from said openings to the spaces between the upright portions thereof.

11. A mold for forming a radiator having end and side walls, headers upon the end walls, substantially parallel fluidways extending between the headers, and fins projecting laterally from the outer sides of said fluidways to said side walls, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending

cores, vertically disposed fin cores arranged one against the other in a row between said enlargements and having substantially horizontal and vertical portions respectively spaced beneath, between and upon the outer sides of said longitudinally extending cores, vertically disposed header cores arranged one against the other between the slabs and fin cores and having substantially horizontal and vertical portions respectively spaced beneath and upon the outer sides of said longitudinally extending cores, and a cover core extending over the vertical portions of said header and fin cores between said slabs, the said slabs being provided in their inner faces with recesses into which metal may flow to form the end walls of the radiator, one of said slabs being provided with an opening for receiving molten metal and having a runner for conducting said metal to the recess therein, the fin cores being provided upon the outer sides of said longitudinally extending cores in horizontal alignment with the recesses aforesaid with recesses into which metal may flow to form the fins of the radiator, the bases of the recesses in the fin cores and the header cores being provided with horizontally aligned slots into which metal may flow to form the side walls of the radiator, the header and fin cores having communicating openings communicating with and adapted to receive molten metal from the opening in the slab aforesaid and having runners for conducting such metal from said openings to the spaces between the upright portions thereof.

12. A mold for forming a radiator having end and side walls, headers upon the end walls, substantially parallel fluidways extending between the headers, and fins projecting laterally from the inner sides of said fluidways, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed fin cores arranged one against the other in a row between said slabs and having substantially horizontal and vertical portions respectively spaced beneath, between and upon the outer sides of said longitudinally extending cores, vertically disposed header cores arranged one against the other between the slabs and fin cores and having substantially horizontal and vertical portions respectively spaced beneath and upon the outer sides of said longitudinally extending cores, and a cover core extending over the vertical portions of said header and fin cores between said slabs, the said slabs being provided in their inner faces with recesses into which metal may flow to form the end walls of the radiator, one of said slabs being provided with an opening for receiving molten metal and having a runner for conducting said metal to the recess therein, the fin cores being provided upon the inner sides of the longitudinally extending cores in horizontal alignment with the recesses aforesaid with recesses into which metal may flow to form the fins of the radiator, the fin and header cores being provided with horizontally aligned slots into which metal may flow to form the side walls of the radiator, the header and fin cores having communicating openings communicating with and adapted to receive molten metal from the opening in the slab aforesaid and having runners for conducting

such metal from said openings to the spaces between the upright portions thereof.

13. A mold for forming a radiator having end and side walls, headers upon the end walls, substantially parallel fluidways extending between the headers, fins projecting laterally from the outer sides of the fluidways to the side walls, and fins projecting laterally from the outer sides of the headers to the side walls, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed fin cores arranged one against the other in a row between said slabs and having substantially horizontal and vertical portions respectively spaced beneath, between and upon the outer sides of said longitudinally extending cores, vertically disposed header cores arranged one against the other between the slabs and fin cores and having substantially horizontal and vertical portions respectively spaced beneath and upon the outer sides of said longitudinally extending cores, and a cover core extending over the vertical portions of said header and fin cores between said slabs, the said slabs being provided in their inner faces with recesses into which metal may flow to form the end walls of the radiator, one of said slabs being provided with an opening for receiving molten metal and having a runner for conducting said metal to the recess therein, the header and fin cores being provided upon the outer sides of the longitudinally extending cores in horizontal alignment with the recesses aforesaid with recesses into which metal may flow to form the fins of the radiator, the bases of the recesses in the fin and header cores having horizontally aligned slots into which metal may flow to form the side walls of the radiator, the header and fin cores having communicating openings communicating with and adapted to receive molten metal from the opening in the slab aforesaid and having runners for conducting such metal from said openings to the spaces between the upright portions thereof.

14. A mold for forming a radiator having side walls, headers between said side walls at opposite ends thereof, and substantially parallel fluidways extending between said headers, comprising substantially parallel longitudinally extending dry sand cores for forming the fluidways, cores of block-like configuration between and cooperating with said longitudinally extending cores for forming the headers, vertically disposed plate-like cores arranged one against the other in a row terminating intermediate opposite ends of said longitudinally extending cores and having substantially horizontal and vertical portions respectively spaced beneath, between and upon the outer sides of said longitudinally extending cores, vertically disposed plate-like cores arranged one against the other in rows at opposite ends of the row aforesaid of plate-like cores and having substantially horizontal and vertical portions respectively spaced beneath and upon the outer sides of said longitudinally extending cores, and a cover core extending over the vertical portions of said plate-like cores and terminating at opposite ends of said longitudinally extending cores, said plate-like cores having aligned slots into which

metal may flow to form the side walls of the radiator, the plate-like cores also having communicating openings adapted to receive molten metal and having runners for conducting such metal from said openings to the spaces between the upright portions thereof.

15. A mold for forming a radiator having side walls, headers between said side walls at opposite ends thereof, substantially parallel fluidways extending between the headers, and fins projecting laterally from opposite sides of said fluidways, comprising substantially parallel longitudinally extending dry sand cores for forming the fluidways, cores of block-like configuration between and cooperating with said longitudinally extending cores for forming the headers, vertically disposed plate-like cores arranged one against the other in a row terminating intermediate opposite ends of the longitudinally extending cores and having substantially horizontal and vertical portions respectively spaced beneath, between and upon the outer sides of said longitudinally extending cores, vertically disposed plate-like cores arranged one against the other in rows at opposite ends of the row aforesaid of plate-like cores and having substantially horizontal and vertical portions respectively spaced beneath and upon the outer sides of said longitudinally extending cores, and a cover core extending over the vertical portions of said plate-like cores and terminating at opposite ends of said longitudinally extending cores between the block-like cores with substantially horizontally aligned recesses into which metal may flow to form the fins of the radiator, the bases of the recesses just mentioned being provided with aligned slots into which metal may flow to form the side walls of the radiator, the plate-like cores having communicating openings for receiving molten metal and having runners for conducting such metal from said openings to the spaces between the upright portions thereof.

16. A mold for forming a radiator having end and side walls, headers upon the end walls, and substantially parallel fluidways extending between the headers, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed plate-like cores arranged one against the other in a row between said slabs and having substantially horizontal and vertical portions respectively spaced beneath, between and upon the outer sides of said longitudinally extending cores, vertically disposed plate-like cores arranged one against the other in rows between the slabs and the adjacent plate-like cores just mentioned and having substantially horizontal and vertical portions respectively spaced beneath and upon the outer sides of said longitudinally extending cores, and a cover core extending over the vertical portions of said plate-like cores between said slabs, said cover core having depending portions between the vertical portions of the plate-like cores, the said slabs being provided in their inner faces with recesses into which metal may flow to form the end walls of the radiator, the plate-like cores having horizontally aligned slots

into which metal may flow to form the side walls of the radiator.

17. A mold for forming a radiator having end and side walls, headers upon the end walls, substantially parallel fluidways extending between the headers, and a partition disposed substantially midway between the fluidways and terminally connected to the headers, comprising substantially parallel longitudinally extending dry sand cores for forming the fluidways, cores of block-like configuration between and cooperating with said longitudinally extending cores for forming the headers, and a casing for said cores comprising slabs at opposite ends of said longitudinally extending cores, vertically disposed plate-like cores arranged one against the other in a row between said slabs and having substantially horizontal and vertical portions respectively beneath, between and upon the outer sides of said longitudinally extending cores, vertically disposed plate-like cores arranged one against the other in rows between the slabs and the adjacent plate-like cores just mentioned and having substantially horizontal and vertical portions respectively spaced beneath and upon the outer sides of said longitudinally extending cores, and a cover core extending over the vertical portions of said plate-like cores between said slabs, said cover core having depending portions between the vertical portions of the plate-like cores, the said slabs being provided in their inner faces with recesses into which metal may flow to form the end walls of the radiator, the plate-like cores being provided substantially in alignment with the outer upright edges of the recesses in the slabs with

aligned slots into which metal may flow to form the side walls of the radiator, the vertical portions of the first mentioned plate-like cores between the longitudinally extending cores aforesaid having aligned slots into which metal may flow to form the partition of the radiator. 5

18. A mold for forming a radiator having side walls, headers between said side walls at opposite ends thereof, and substantially parallel fluidways extending between said headers, comprising substantially parallel longitudinally extending dry sand cores for forming the fluidways, cores of block-like configuration between and cooperating with said longitudinally extending cores for forming the headers, vertically 10 15 20 25 30 disposed plate-like cores arranged one against the other in a row terminating intermediate opposite ends of said longitudinally extending cores and having substantially horizontal and vertical portions respectively spaced beneath, between and upon the outer sides of said longitudinally extending cores, vertically disposed plate-like cores arranged one against the other in rows at opposite ends of the row aforesaid of plate-like cores and having substantially horizontal and vertical portions respectively spaced beneath and upon the outer sides of said longitudinally extending cores, and a cover core extending over the vertical portions of said plate-like cores and terminating at opposite ends of said longitudinally extending cores, said cover core having depending portions between the vertical portions of the plate-like cores, said plate-like cores having aligned slots into which metal may flow to form the side walls of the radiator. 35
